UNITED STATES PATENT OFFICE.

OLE OLSEN, OF OAKLAND, ASSIGNOR OF ONE-HALF TO CHARLES GREENE,
OF SAN FRANCISCO, CALIFORNIA.

HAIR-CLIPPING MACHINE.

SPECIFICATION forming part of Letters Patent No. 511,966, dated January 2, 1894.

Application filed August 25, 1893. Serial No. 484,038. (No model.)

To all whom it may concern:

Be it known that I, OLE OLSEN, a subject of the King of Sweden and Norway, residing in Oakland, Alameda county, State of California, 5 have invented an Improvement in Hair-Clipping Machines; and I hereby declare the following to be a full, clear, and exact description of the same.

My invention relates to that class of hair- 10 clipping machines in which a reciprocating toothed plate works upon a fixed tooth plate.

My invention consists in the novel details 15 of construction, arrangement and combination which I shall hereinafter fully describe and specifically claim.

The object of my invention is to provide a hair-clipping machine which, by reason of the hinge connection between its handle and head, may be adjusted to varying positions, thus 20 adapting it for the most convenient operation under all circumstances and in different places.

Referring to the accompanying drawings 25 for a more complete explanation of my invention,—Figure 1 is a perspective view of my hair clipping machine. Fig. 2 is a plan of the head portion, the handle sleeve being in section. Fig. 3 is a central longitudinal vertical section.

30 A is the main or fixed plate having the teeth a.

B is the reciprocating plate having the teeth b adapted to work upon the teeth a in the usual manner.

35 From the rear edge of the main plate A rise brackets C, the forward ends of which fit in a groove b' in the plate B whereby said plate is accurately guided in its movement. These brackets are formed with spring tops c' regulated by screws c² extending upwardly from 40 the main plate, and in these brackets and their spring tops are formed bearings in which are pivoted the journals d of a yoke D which said yoke forms part of or is secured to the handle sleeve E.

45 In the journals d of the yoke is mounted a reciprocating shaft F which carries at its middle a collar f having in its back edge an elongated groove f', and in its forward edge a rib 50 or flange f², said groove and said flange being

circumferential of the collar. The back of the collar is squared off to abut against the face of the yoke D, whereby the collar is turned with the yoke and handle sleeve. The rib or flange f² fits down into and plays in the groove 55 seat b² in the reciprocating or movable plate B.

Extending through the handle sleeve E is the rotary shaft G having at its inner end an eccentrically located pin or crank stud g which fits in the groove f' of the collar f of shaft F. 60

From the construction of the device as thus far described it will be seen that when the shaft G is rotated, it will, through its eccentric pin or crank stud g acting in the groove of the collar f, cause the shaft F to move back 65 and forth in the direction of its length, said shaft playing through the journals d of the yoke D. This movement of the collar, acting through its rib or flange f² which engages the plate B, will cause the reciprocation of said 70 plate.

It will be seen also from this construction that the connection between the handle portion of the machine and what may be termed the head portion, and which consists of the two-toothed plates, with their brackets, 75 is a hinged one, adapting the two portions to be turned to various positions with relation to each other. Thus, for example, the tooth plates may be turned to a plane below and parallel with the line of direction of the handle, with their teeth extending forwardly;

and again the plates may be turned at right angles to the line of handle, or by a further movement the plates may be turned to a plane above the handle and parallel with its direction, the teeth extending backwardly, and it is obvious that positions between these limits may be reached. These adjustments enable 80 the machine to be used conveniently in any position and to be operated in various here- 85 tofore inaccessible places, or in places accessible only by the most inconvenient positions of the operator. It will also be seen that by reason of the construction of the power-transmitting connections described, these latter re-

main in engagement in whatever position the two parts of the machine may be turned. 90
95 The means for operating the shaft G are as follows: The end of the shaft G carries a bevel pinion g' with which engages a bevel gear H 100

which is connected with a winding arbor I by the usual pawl and ratchet connection represented by i, said arbor having a power spring J. These parts are all contained within a box 5 K which is secured to the end of the sleeve E by means of a nut L screwed into the sleeve and secured to the box, said nut also acting as a stop against the reduced end of the shaft G whereby the pinion of said shaft 10 is held to its engagement with the main gear.

Upon the handle sleeve is an ordinary handle M, over the inner end of which is adapted to fit a slidable ferrule or ring N, to which is attached a rod n extending backwardly and 15 adapted to enter and to be withdrawn from a hole in the pinion g'. Upon winding the spring arbor, its energy may be preserved by moving the ferrule or ring in one direction whereby the rod n will enter the hole of the 20 pinion g' and prevent the parts from turning.

When it is desired to use the machine, the ferrule or ring is slipped in the other direction thereby withdrawing the rod from the pinion and freeing the parts.

Having thus described my invention, what I claim as new, and desire to secure by Letters Patent, is—

1. A hair-clipping machine, having its head portion which carries the toothed plates 30 loosely suspended from the handle portion and capable of swinging about its point of suspension to enable its position to be changed from a horizontal position parallel with and below the handle with the teeth extending 35 forwardly, to a position parallel with and above the plane of the handle with its teeth extending rearwardly.

2. In a hair-clipping machine, the combination of the head portion consisting of the 40 fixed and the movable toothed plates, a handle portion, a slidable shaft connected with the movable plate and forming a hinge connection between the head and handle portions, whereby the two may be turned into 45 various positions with relation to each other, and power transmitting mechanism comprising a rotatable shaft having an eccentric connection with the slidable shaft for operating the movable plate, adapted to remain in engagement in whatever position the head and 50 handle portions may be placed, substantially as herein described.

3. In a hair-clipping machine, the combination of a fixed toothed plate, a reciprocating toothed plate operating thereon, a handle 55 hinged to the fixed plate upon an axis that is parallel with the plane of the toothed plates whereby it may be turned to various positions with relation to the toothed plates, a 60 rotatable shaft and an eccentric connection between said shaft and the reciprocating

plate whereby the latter is operated, substantially as herein described.

4. In a hair-clipping machine, the combination of the fixed and the reciprocating 65 toothed plates, the handle sleeve having journals pivotally seated in bearings on the fixed plate, the slidable shaft mounted in said journals and having the collar with a rib or flange engaging a groove in the reciprocating 70 toothed plate, and the rotatable shaft with its eccentric or crank pin engaging a groove in the collar, substantially as herein described.

5. In a hair-clipping machine, the combination of the fixed and reciprocating toothed 75 plates; the handle sleeve having a yoke with journals pivotally seated in bearings on the fixed plate, the slidable shaft mounted in said journals and having a collar abutting upon the yoke, said collar having on its front a 80 flange or rib engaging a groove on the reciprocating plate, and in its back a groove, and the rotatable shaft in the handle sleeve having an eccentric or crank pin engaging the groove in the back of the collar, substantially 85 as herein described.

6. In a hair-clipping machine, the combination of the fixed and reciprocating toothed plates, the handle sleeve pivoted thereto, a 90 rotatable shaft in the sleeve and connections between said shaft and the reciprocating plate for operating the latter, the spring driven gear at the end of the handle sleeve, and a pinion on the rotatable shaft engaging said gear, substantially as herein described.

7. In a hair-clipping machine, the combination of the fixed and reciprocating toothed plates, the handle sleeve pivoted thereto, a 95 rotatable shaft in the sleeve and connections between said shaft and the reciprocating plate for operating the latter, the spring driven gear at the end of the handle sleeve, a pinion on the rotatable shaft engaging said gear, the sliding ferrule or ring and the rod thereof engaging and relieving the pinion for throwing the 100 power mechanism into and out of action, substantially as herein described.

8. In a hair-clipping machine, the combination of the power transmitting shaft, the handle sleeve through which it passes, the 110 box or casing having the nut screwed into the handle sleeve and embracing a reduced end of the power shaft and spring actuated gearing within the box or casing for transmitting power to the shaft, substantially as herein described.

In witness whereof I have hereunto set my hand.

OLE OLSEN.
